UNITED STATES PATENT OFFICE.

JOHN D. RICHARDSON, JR., OF NEWPORT, RHODE ISLAND.

TELEPHONE SWITCH-SIGNAL.

SPECIFICATION forming part of Letters Patent No. 240,184, dated April 12, 1881.

Application filed January 8, 1881. (Model.)

To all whom it may concern:

Be it known that I, JOHN D. RICHARDSON, Jr., of Newport, in the county of Newport and State of Rhode Island, have invented a new and Improved Telephone Switch-Signal, of which the following is a full, clear, and exact description.

In telephone-exchange systems, where it is necessary to have six or eight stations connected with one line-wire, it is desirable that the telephone-switches be placed correctly after using for speaking purposes, for if left in a wrong position there is much trouble and delay in finding and remedying the fault. To overcome this I have invented a telephone switch-signal that reminds the person using the telephone, either by visible signals or by vibrations of the call-bell, to place his switch in the right position, or that his switch is wrongly placed, thus preventing the switch from being left in a wrong position, and saving time and trouble in finding and locating the misplaced switch.

The invention consists of a signal-plate indicator or disk moved by a lever connected with the switch-lever hook of a telephone-switch, and in the drawings is shown connected with a Bell-telephone switch-bell.

Figure 1 is a front elevation of the switch-signal attached to a telephone switch-bell. Fig. 2 is a plan of the same. Fig. 3 is an end elevation of the telephone switch-signal. Fig. 4 is a front elevation, showing the electrical connections of the device.

Similar letters of reference indicate corresponding parts.

In the drawings, A' represents the switch-hook on the end of a switch-lever, A, on which the telephone is hung, with the effect of keeping the switch closed, a ground-plate, C', being attached to the back of said lever A, the weight of the telephone keeping it (the lever) in contact with the plates B C.

F G represent the line-wire posts, and G² the ground-wire post. E are the telephone-posts, H, the armature, and M the magnet, all on the frame M'.

N represents the switch signal-lever resting on the switch-hook A', and having one end pivoted at a to a stud, N', that projects from the plate N², which is fastened on the insulating-plate P²; and O is a strip of rubber or

other insulating substance, to prevent electric connection between the switch signal-lever N and the switch-lever A, which latter is hitched to the signal-lever N by a wire, I, that allows said lever A a lateral movement.

P represents two platinum springs, that depend from the plate P' and hug the lever N when the latter is raised, said plate P' being secured on the insulating-plate P².

D is a signal-plate or indicator, on which may be inscribed any sign or warning. Said disk D or indicator is hinged at b on a plate, D², that is fixed on the insulating-plate P², and is raised and lowered by the bent rod D', or other suitable device, which connects it with the lever N.

L is a small upright post, in electrical connection with the plate N², and having a platinum spring, L'', attached thereto at right angles.

R is the receiver, and S is the lightning-arrester.

When this apparatus is placed on a switch-bell, the spring L'' is between the armature H and core of the magnet M, pressing on the armature H, but not touching it when said armature H is off.

The springs P are connected with ground-wire post G² by wire c, and the frame M' is connected with line-wire F' by wire d.

When the switch is in place the switch signal-lever N will not touch the springs P, and the disk D or indicator is brought down flat, not showing any sign.

When the telephone is switched in, the switch signal-lever N rises with the switch-lever A, and is pressed by springs P. As the battery is taken off when the telephones are used, the short circuit will have no effect on the bell-magnet M; but if the switch remain so after the conversation is ended, then when the battery is put on the bell Q will ring violently until the switch is placed right, and then the switch signal-lever N falls from the springs P.

The disk D or indicator lifts every time the switch is moved through the medium of the rod D', and thereby gives notice to the user of a connected telephone to set the switch correctly before leaving. Said disk or indicator D may be used without the short circuit. They may be used separately or together.

When the switch A is down, the electric

current passes through the wire F', post F, wire F², magnet M, wire M², plate C, switch-lever A, plate B, wire B', post G, and out on wire G'. When the switch is up the lever N is also up, and the current then passes successively through the wire F', post F, wire F², magnet M, wire M², plate C, ground-plate C', telephone R, plate S, and ground-plate G²; but when the armature H is drawn up to touch the spring L'', the magnet M is cut out or short-circuited, the current passing from the wire F' through post F, wire d, frame M', armature H, springs L'', post L, plate N², lever N, springs P, wire e, and ground post and wire G². As soon as contact between the armature H and spring L'' is broken, the current passes directly through the magnet M, and the armature H is again attracted. When the lever A is up the connections are made in the usual way for talking with the telephone.

Having thus described my invention, I claim as new and desire to secure by Letters Patent—

1. In a telephone switch-signal, the indicator or plate D, provided with a connecting-link, D', in combination with switch-lever A, substantially as described.

2. A telephone switch-signal consisting of lever N, pivoted at a, spring P, plates P' and P'', plate D, post L, and spring L'', as and for the purposes described.

3. A telephone switch-signal constructed substantially as herein shown and described, consisting of pivoted signal-lever N, stud and plate N' N², springs and plate P P' and insulating-plate P², post and spring L L², and indicator-rod and plate D D' D², arranged and operated as set forth.

4. The combination, with a telephone-switch, of the signal-lever N, provided with insulator O, wire I, stud and plate N' N², springs and plate P P', insulating-plate P², post and spring L L², and indicator-rod and plate D D' D², as and for the purpose substantially as herein described.

5. In a telephone switch-signal, the combination, with the pivoted signal-lever N, stud and plate N' N², rod D', and hinged indicator D, of the springs P, substantially as and for the purpose described.

JOHN D. RICHARDSON, JR.
